UNITED STATES PATENT OFFICE.

ROBERT G. JOHNSTON AND GEORGE A. BUFFINGTON, OF ORCHARD,
NEBRASKA.

VENT-STOPPER FOR PUMPS.

SPECIFICATION forming part of Letters Patent No. 375,635, dated December 27, 1887.

Application filed July 21, 1887. Serial No. 244,910. (No model.)

To all whom it may concern:

Be it known that we, ROBERT G. JOHNSTON and GEORGE A. BUFFINGTON, citizens of the United States of America, residing at Orchard, 5 in the county of Antelope and State of Nebraska, have invented certain new and useful Improvements in Vent-Stoppers for Pumps; and we do hereby declare the following to be a full, clear, and exact description of the invention, such as will enable others skilled in the art to which it appertains to make and use the same, reference being had to the accompanying drawings, and to letters or figures of reference marked thereon, which form a part 10 of this specification.

Our invention relates to certain new and useful improvements in vent-stoppers for pumps, the object of our invention being to provide a cheap, simple, and effective means 20 whereby the water can be let out of the pump-stock, so as to prevent the pipe or stock bursting, which would be occasioned by the water freezing therein, our improvement being adapted to be applied to metal tubes which 25 are used for pump-stocks, or on pump-stocks of ordinary construction.

In the accompanying drawings, which illustrate our invention, Figure 1 is a view showing our improved vent-stopper applied to a 30 pump of ordinary construction. Fig. 2 is a longitudinal sectional view, and Fig. 3 is a transverse sectional view taken through the line *xx* of Fig. 2.

A refers to the pump, which is suitably 35 connected to the pump-stock or well-tube B, which is usually a metal tube. The pump pipe or stock A may have pivoted thereto, as shown in Fig. 1, a bell-crank lever, *a*, which is adapted to be turned upon its pivot by the 40 foot of the person who operates the pump. This bell-crank lever may be provided with an automatic catch, or a catch of any suitable construction—as a pin for holding the same in position—so as to maintain the vent-stopper in 45 an elevated position. The opposite end of the bell-crank lever *a* is connected to the rod or wire (rust-proof) C. Said lever becomes a self-locker by the end to which the wire is at-

tached passing a little past the perpendicular when raised.

D refers to a metallic plate, which is curved centrally, so as to embrace a portion of the well-tube B, said plate being provided with side flanges, *d d*, which are perforated at suitable intervals for the reception of metallic 55 straps E, F, and G, which are bolted to the plate D, so as maintain said plate in position upon the tube or pump-pipe B. The tube or pump stock or pipe B has at a suitable distance from the pump, below the freezing-point 60 or just above the cylinder, a vent, *v*. The strap is provided centrally with a projecting portion, *e*, into which passes the rod C, said rod carrying beneath the strap E a washer, *f*, against which abuts a spiral spring, H, the 65 opposite end of said spring abutting against the upper surface of the wedge-shaped sliding valve I. The straps F and G each serve as guides for the edge-shaped sliding valve I, and the projecting portion of these straps taper or are wedge-shaped, so as to conform with 70 the wedge-shaped valve. The wedge-shaped valve I is provided on its surface adjacent to the pump stock or tube B with a packing, *i*, which is suitably secured thereto. Said valve 75 is of such a length that the upward movement of the rod C cannot displace the same from the guides. The lower end of the valve I is of much less thickness than the upper portion, the inner side thereof being cut away or removed, so that when the sliding valve is elevated the vent will be uncovered. The vent 80 is located near the lower valve in the pump tube or stock.

We are aware that prior to our invention 85 it has been proposed to construct vent-stoppers having a sliding gate which is connected to a rod, so that when said gate is elevated by the rod the vent will be opened; also, that it has been proposed to construct vent-stoppers 90 with spiral spring for holding the gate or slide down over the vent in the pump, and we do not claim such construction as our invention; but

What we claim as new, and desire to secure 95 by Letters Patent, is—

In a vent-stopper for pump-tubes, the plate D, having side flanges, straps E, F, and G, for holding said plate in position upon the pump pipe or stock said straps having centrally-projecting portions, the projecting portions of the straps F and G being tapered, and a wedge-shaped sliding valve and an operating-rod, substantially as shown, and for the purpose set forth.

In testimony whereof we affix our signatures to in presence of two witnesses.

ROBERT G. JOHNSTON.
GEORGE A. BUFFINGTON.
